CHARLES W. REINOEHL AND BENT L. WEAVER, OF STEELTON, PENNSYLVANIA.

RAILROAD-SWITCH.

No. 919,950.

Specification of Letters Patent.

Patented April 27, 1909.

Application filed July 20, 1908. Serial No. 444,532.

To all whom it may concern:

Be it known that we, CHARLES W. REINOEHL and BENT L. WEAVER, citizens of the United States, and residents of Steelton, 5 Dauphin county, State of Pennsylvania, have invented certain new and useful Improvements in Railroad-Switches, of which the following is a full, clear, and exact description, reference being had to the accompanying drawings.

This invention relates to that class of railroad switches wherein are employed a main rail having a head, a base, and a web connecting the head and base; a lead rail having 15 a head, a base, and a web connecting the head and base; and a movable switch rail having a head, a base, and a web connecting the head and base; said switch rail having one end connected to the lead rail and the 20 other end made tapering, and movable toward and from the main rail. Heretofore, in manufacturing switches of this character, it has been the practice to produce the tapering switch rail from a regular stock rail of the 25 same character as the main and lead rails, by cutting down the regular stock rail to form the tapering portion of the switch rail. The tapering portion of the switch rail thus constructed was very weak and would not 30 long stand the lateral thrust of the car wheels thereagainst. Attempts have been made to strengthen the tapering portion of the switch rails thus constructed by applying reinforcing members to the sides of the webs 35 of the tapering portions of the switch rails, and to secure said members to the rails by bolts passing through holes in said members and rails. This construction strengthened the tapering switch rail to some extent, but 40 it had its defects in that it was necessary to perforate the parts in order to apply the bolts thereto.

The object of the present invention is to 45 overcome the objections above mentioned, and to provide a railroad switch having a strong and durable tapering switch rail made of a single piece of metal, as will be herein-after fully described and claimed.

In the drawings:—Figure 1 is a plan view 50 of a railroad switch embodying our invention. Fig. 2 is a transverse section, as on the line 2—2 of Fig. 1. Fig. 3 is a transverse section as on the line 3—3 of Fig. 1. Fig. 4 is a horizontal section as on the line 4—4 of Fig. 3, the cross ties and supporting plate be-

ing omitted. Fig. 5 is a plan view of the switch rail detached.

5 designates the main rail, comprising a head 6, a base 7, and a vertical web 8 connecting the head and base. The main rail is 60 supported upon plates 9 which rest upon underlying cross-ties 10, the rail 5 and plates 9 being secured to the cross-ties in the usual manner.

11 designates the lead rail, arranged adjacent the main rail, and comprising the head 12, base 13, and vertical web 14 connecting the head and base.

15 designates the switch rail resting upon the plates 9, and comprising a head 16, base 70 17, and vertical web 18 connecting the head and base. One end of the switch rail 15 is adjacent the end of the lead rail 11, and forms a continuation thereof, and the other or free end of the switch rail 15 is movable 75 toward and from the main rail 5.

The free end of the head of the switch rail is made tapering, as shown, and the base 17 of the switch rail is made tapering, as shown, so that the base of the switch rail 15 may be 80 moved over the base 7 of the main rail 5 and the tapering pointed head 16 of the switch rail may be moved into engagement with the head of the main rail.

The switch rail 15 is made of a single piece 85 of metal, and the web 18 of the tapering portion or free end of the switch rail is made of greater thickness than the thickness of the webs of the main and lead rails, and the web of the end of the switch rail 15 adjacent the 90 lead rail 11 is reduced to the thickness of the web of the lead rail 11 or substantially so, to receive a splice bar 19 which extends between the switch rail 15 and the lead rail 11 and is secured thereto by means of bolts 20, the 95 bolts 20 and splice bars 19 being sufficiently loose to permit the switch rail 15 to be moved toward and from the main rail 5.

The portion of the web of the tapering switch rail which is made thicker than the 100 webs of the main and lead rails, preferably extends from the point of the switch rail to or near the splice bar 19, and the web 18 at and near the point thereof extends laterally of the head 16, which is greatly reduced at 105 the free end of the switch rail.

We have found that the construction above described provides a strong and durable tapering switch rail made of a single piece of metal, free from objectionable sepa- 110

rate reinforcing or strengthening parts, and an improved switch rail may be produced by rolling a single piece of steel into the described form by rollers designed for that purpose.

5 Having thus described our invention, we claim as new and desire to secure by Letters Patent:—

1. In a railroad switch, the combination of the main rail having a head, a base, and a 10 web connecting the head and base; the lead rail having a head, a base, and a web connecting the head and base; the switch rail movable toward and from the main rail and having a tapering free end, a head, a base, 15 and a web connecting the head and base formed of a single piece of metal extending from the point end of the switch rail to the lead rail, the web of the tapering portion being of greater thickness than the thickness of the webs of the main and lead rails, and means connecting the switch rail with the lead rail, substantially as described.

2. In a railroad switch, the combination

of the main rail having a head, a base, and a web connecting the head and base; the 25 lead rail having a head, a base, and a web connecting the head and base; the switch rail movable toward and from the main rail and having a tapering free end, a head, a base, 30 and a web connecting the head and base formed of a single piece of metal, the web of the tapering portion being of greater thickness than the thickness of the webs of the main and lead rails, and the web of the switch rail adjacent the lead rail being reduced to the thickness of the web of the lead rail; and a splice bar bolted to the meeting ends of the switch and lead rails, substantially as described.

In testimony whereof, we have hereunto 40 affixed our signatures.

CHARLES W. REINOEHL.
BENT L. WEAVER.
